UNITED STATES PATENT OFFICE

1,926,724

APPARATUS FOR HEATING, THAWING, AND DRYING CONCRETE AGGREGATES

Charles S. Johnson, Champaign, Ill.

Application December 10, 1930
Serial No. 501,182

2 Claims. (Cl. 34—34)

In the production of concrete, it is usual to keep a supply of the aggregates in an overhead bin having a discharge opening or openings in its lower portion through which the aggregates are discharged into a measuring or weighing batcher. The aggregates usually contain more or less moisture and therefore during cold weather the contents of the bin are likely to freeze so as to interfere with the discharge of the material from the bin. Water collecting in the lower portion of the bin may freeze into a solid mass. When freezing has occurred, it has been customary to thaw the aggregates by blowing steam into the bin, but this has resulted in increasing the moisture content of the aggregates and has produced a liability to serious variations in the strength of the concrete.

The object of the present invention is to provide a method and means of heating and thawing aggregates which shall be free from the objections incident to increase in the moisture content of the aggregates and which shall at the same time be more economical. This object I attain by introducing into the lower portion of the mass of aggregates hot, dry gases, as, for example, the products of combustion of solid or liquid fuel. The invention will be more fully understood by reference to the accompanying drawing, in which

30 Figure 1 is an elevation of a bin equipped with apparatus embodying the features of my invention.

Fig. 2 is a plan view.

35 Figs. 3 and 4 are diagrams showing alternative constructions.

While the bin may be of any desired form and construction, I have herein illustrated a bin 1 similar to the one shown in my Patent No. 1,754,516, dated April 15, 1930, said bin being 40 octagonal in horizontal cross-section and being tapered toward its lower end. If desired, the bin may be provided with vertical partitions 2, whereby the interior of the bin is divided into four compartments, each of said compartments 45 having a discharge opening 3 at its lower end. The means for controlling discharge through the openings 3 may be of any preferred character and therefore has been merely indicated diagrammatically herein by means of a dotted line 4.

50 One or more chambers are located within the lower portion of the bin to which hot gases may be supplied. Preferably, and as herein shown, four chambers 5 are provided at the angles formed between the partitions 2. These chambers are closed except for louvers 6, said louvers serving to permit the escape of gases into the aggregates that surround the chambers 5, while at the same time preventing the aggregates from entering the chambers.

60 Means of any preferred nature may be em-

ployed for generating hot gases and for supplying them to the chambers 5. In Fig. 1 I have shown a stove or furnace 7 having a flue 8 for the escape of the products of combustion, said flue being connected to the suction side of a blower 9. The outlet of the blower 9 is connected by means of a pipe 10 to a manifold 11 from which pipes 12 extend to the chambers 5. If desired, a shut-off valve 13 may be connected into each of the pipes 12 so that any chamber may be shut off and so that the flow of gases may be regulated. An air inlet 14 may be provided in the flue 8 so that the hot gases may be diluted, if desired.

When it is desired to heat, dry or thaw the contents of the bin, hot gases generated in the heater 7 are forced by means of the blower 9 into the chambers 5, whence the gases escape through the louvers 6 and permeate the mass of aggregates in the bin. It will be seen that frozen aggregates will not only be thawed and heated but also dried. Moreover, the heat is applied more economically than when steam is used, because the heat losses involved in the vaporization of water to form steam are avoided.

The apparatus shown in Fig. 1 may be modified in various ways. Thus the blower 9 may be omitted and the hot gases allowed to flow through the chambers 6 under the pressure generated within the heater 7^a, as indicated diagrammatically in Fig. 3. Fig. 4 illustrates another modification employing an oil burner 15 of the well-known type that comprises a fan 16 for supplying a relatively large volume of air at low velocity to support the combustion of oil.

I claim as my invention:

1. The combination of an imperforate bin having a discharge opening at its lower end and vertical partitions dividing the bin into a plurality of compartments all discharging through said opening and arranged around the central axis of the bin, a chamber for hot gases, adjacent the said discharge opening, and at the center of the bin, and having louvers communicating with the compartments to discharge hot gases therefrom into the bin and upwardly through the material therein, and means for supplying hot gases to said chamber.

2. The combination stated in claim 1, the chamber for hot gases being divided by the partitions into separate sections, and valve means to selectively supply the separate sections with hot gases respectively.

CHARLES S. JOHNSON.
